Primary Examiner — Richard Kearney*Assistant Examiner* — Anthony Vincent Rotolo(74) *Attorney, Agent, or Firm* — Nitin Kaushik(57) **CLAIM**

The ornamental design for a grow light, as shown and described.

DESCRIPTION

FIG. 1 is a front perspective view of a grow light, showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof;

FIG. 8 is an enlarged detail view of area 8 in FIG. 1;

FIG. 9 is an enlarged detail view of area 9 in FIG. 6; and, FIG. 10 is an enlarged detail view of area 10 in FIG. 7.

The broken lines in the drawings illustrate the portions of the grow light which form no part of the claimed design. Additionally, the short-dash-long-dash broken line circles in FIGS. 1 and 7 indicate portions of the design that are enlarged to show detail in FIGS. 8 and 9; the short-dash-long dash circles form no part of the claimed design.
